SPIKE ATTACHMENT FOR SHOES

Filed April 30, 1931

Fig. 2.

The diagram illustrates a medical device assembly. It features a main tube 10 with a side tube 9 attached. A connector 11 is positioned on the main tube 10, secured by a screw 12. A stopper 13 is also present on the main tube 10. The assembly is shown in two views, one above the other, with labels 9, 10, 11, 12, and 13 pointing to specific components.

John L. Kerr,
INVENTOR
BY
C. L. Evans
ATTORNEY

UNITED STATES PATENT OFFICE

JOHN LAW KERR, OF ALBANY, GEORGIA

SPIKE ATTACHMENT FOR SHOES

Application filed April 30, 1931. Serial No. 534,071.

This invention relates to attachment for shoes, and its general object is to provide a spike bearing device that can be detachably associated with any type of shoes, in an easy and expeditious manner without fear of casual displacement or loss of the device, with the result the device will adapt ordinary shoes for use in playing golf and other purposes where spiked shoes are desired or necessary.

A further object of the invention is to provide a spike bearing device that is formed from wire and is held associated with shoes by the inherent resiliency of the wire.

Another object of the invention is to provide a spike device that is adapted to be detachably associated with shoes and renders ordinary shoes capable of performing all the functions of spiked shoes that have spikes permanently fixed thereto.

A still further object of the invention is to provide a spike device that is simple in construction, inexpensive to manufacture, easy to install and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a top plan view of one form of my invention applied to a shoe sole.

Figure 2 is a modified form.

Referring to the drawing in detail and particularly to Figure 1, the letter A indicates a shoe sole which receives the device in the manner as illustrated in Figure 1, and the device in this form is provided with a pair of cooperating single strands of resilient wire which are of identical shape but for distinction are indicated by the reference numerals 1 and 2.

Each of the strands of wire 1 and 2 have their ends bent at right angles to form what may be termed jaws 3 which are in the form

of studs, and from the jaws 3 the strands of wire are curved upon themselves, thence are bent to form L-shaped members 4 which provide spikes, the long arms of the L-shape members 4 being disposed in contacting engagement with the bottom of the sole of the shoe, while the short arms act in the capacity as ground penetrating elements.

The strands of wire are twisted in coil formation about each other midway between their ends, and midway between the ends of the coiled portion which is indicated by the reference numeral 5, the strands extend laterally in opposed relation to provide intermediate L-shape members 6.

In forming the substantially L-shape members 4 and 6, it will be noted that the portions of the wire providing these members are arranged in contacting engagement, and due to the fact that the long arms of the L-shape members are arranged in engagement with the bottom of the sole, it will be apparent that the pressure upon the long arms will urge the ground penetrating portions downwardly, and in a manner whereby displacement of the members or bending the same out of shape is reduced to a minimum.

In the form of the invention as shown in Figure 2, I also employ two strands of wire shaped substantially similar to the strands 1 and 2, and for distinction the strands of the wire as shown in Figure 2 are indicated by the reference numerals 7 and 8. Each of the strands 7 and 8 are curved in substantially semi-circular formation and includes jaws 9 for engagement with the shoe soles, and substantially L-shape spike members 10. Each of the strands 7 and 8 have formed midway the ends thereof an eye 11 for the purpose of accommodating a screw shaft 12 having left hand threads for half of its length, while the remaining half is provided with right hand threads. These threads receive nuts 13, and one of the ends of the screw shaft 12 is squared to accommodate a key or a tool whereby the shaft is rotated for disposing the strands 7 and 8 with respect to each other, it being apparent that by rotating the shaft in one direction, the strands 7 and 8 will be moved away from each other and by rotating

the shaft in an opposite direction, the strands 7 and 8 will be moved toward each other.

From the above description and disclosure of the drawing, it will be obvious that I have 5 provided a spike device that can be utilized on ordinary shoes so as to cause the latter to perform the function of spike shoes or shoes that have spikes permanently fixed thereto and due to the inherent resiliency of the 10 strands of wire from which I provide the spike devices, the devices are capable of fitting practically all sizes of shoes and are held upon the sole of the latter by the pressure of the jaws against the outer edges of 15 the soles in a manner to prevent casual displacement or loss of the devices. The form as shown in Figure 2, has of course a greater latitude of adjustment and will probably fit every size of shoe.

20 It is thought from the foregoing description that the advantages and novel features of my invention will be readily apparent.

I desire it to be understood that I may make changes in the construction and in the combination and arrangement of the several parts, provided that such changes fall within 25 the scope of the appended claims.

What I claim is:

1: A spike attachment for shoes comprising 30 strands of resilient wire bent in substantially semi-circular formation, and coiled about each other midway their ends, jaws formed with the ends of said strands and being engageable with the sole of a shoe for detachably securing the attachment to said sole, spike means formed with said strands and being substantially L-shaped, and said spike means having their long arms engageable with the sole and their short arms extending 35 at right angles with respect to the long arms to provide ground penetrating means.

2. A spike attachment for shoes comprising 40 a pair of strands of resilient wire bent in curved formation and being coiled about each other midway their ends, jaws formed with the ends of said strands and engageable with the sole of a shoe for detachably securing the attachment to said sole, said strands 45 being bent at intervals intermediate their ends to provide substantially L-shaped spike means, and L-shape spike means formed with said strands and extending in opposed relation from the coil portion.

55 In testimony whereof I affix my signature.
JOHN LAW KERR.
